(No Model.)

J. BURRY.

MOTOR.

No. 332,048.

Patented Dec. 8, 1885.

UNITED STATES PATENT OFFICE.

JOHN BURRY, OF FORT RENO, INDIAN TERRITORY.

MOTOR.

SPECIFICATION forming part of Letters Patent No. 332,048, dated December 8, 1885.

Application filed September 30, 1885. Serial No. 178,631. (No model.)

To all whom it may concern:

Be it known that I, JOHN BURRY, of Fort Reno, Indian Territory, have invented a new and Improved Motor, of which the following 5 is a full, clear, and exact description.

The object of my invention is to provide a new and improved motor, which is simple in construction, effective in operation, and can be driven by either water, steam, compressed 10 air, gas, or other fluid.

The invention consists of two disks placed in a shell, of a driving-wheel mounted on a shaft and having recesses in which are sliding arms or pistons rotating loosely on a shaft 15 which is eccentric to the driving-shaft, and of cross-bars to cut off the incoming and outgoing currents.

The invention also consists in various parts and details hereinafter more fully set forth and 20 described.

Reference is to be had to the accompanying drawings, forming part of this specification, in which similar letters of reference indicate corresponding parts in both the figures.

25 Figure 1 is a longitudinal vertical section on the lines *x x* of Fig. 2, showing my improvement. Fig. 2 is a vertical cross-section of the same on the lines *y y*, Fig. 1.

The disks A and B are placed a suitable 30 distance apart to form the space C, and are encircled by the shell or band D, provided with the inlet-opening D' and the outlet-opening D''. The shaft E is mounted in any suitable manner in the disk A, and is provided 35 on its outside with a crank, E', or a pulley, and provided on its inner end, which projects into the space C, with a wheel, F, having the recesses F', and provided with the rim F'', the outer edges of which bear against the inner 40 faces of the disks A and B. The disk B is provided in its center with a pin, G, projecting inwardly into the space C and attached to the disk B in any suitable manner. The shaft E and the pin G are placed in an eccentric position 45 to each other, the pin G being in the center of the disk B, and the shaft E being located above the pin G in the disk A, centrally of the wheel F. The pin G has a reduced portion, G', which forms a bearing for the inner ends of 50 the sliding arms or pistons H. The latter extend radially from the center of the pin G, and

are placed with their outer ends, H', in the recesses F', formed in the wheel F. The inner ends of the pistons H are formed with eyes H'', arranged to fit on the pin G, as shown. The 55 upper ends, H', of the pistons H are as wide as the rim F'' of the wheel F, and as the wheel F and the arms H are eccentric with each other the upper ends, H', recede or advance in the recesses F' of the wheel F when the motor 60 is in motion. The segmentally-shaped cross-piece I is secured between the disks A and B at their lower edges, and the segmentally-shaped cross-piece J is attached between the disks A and B at their upper edges. Both 65 cross-pieces I and J, in conjunction with the wheel F and the sliding arms H, divide the space C in two halves, of which one is in direct connection with the inlet-opening D' and the other in direct communication with the 70 outlet-opening D''.

The operation is as follows: The fluid by which the motor is driven enters the space C through the opening D', and exerts its pressure against that part of the arms H which 75 project beyond the rim F'' of the wheel F, causing the arms H and the wheel F to rotate in the direction of the arrow a', and also causing the arm H to assume the farthest outward position beyond the rim F'' on reaching the center of the cross-piece I. As soon as one of the arms H leaves the rear end of the cross-piece I, the next following arm H will enter on the front end of the cross-piece I, so that the fluid which caused the arms H to rotate will flow 80 out through the opening D'', and cannot flow back to the first half of the space C on account of the cross-pieces I and J. The rotation of the wheel F causes the shaft E and the crank-arm E' to rotate, and the power thus obtained can 85 be utilized in any desirable manner by proper connections with the crank arm E'.

The motor can be very effectually used as a pump or a blower.

Having thus described my invention, what I 95 claim as new, and desire to secure by Letters Patent, is—

1. In a motor, the disk A, the shaft E, the wheel F, having the recesses F' and the rim F'', in combination with the disk B, the stud G, the 100 arms H, the cross-pieces I and J, and the casing D, substantially as shown and described.

2. In a motor, the disks A and B, the shaft E, the wheel F, having the recesses F' and the rim F², the stud G, and the arms H, in combination with the cross-pieces I and J and the casing D, having the openings D' and D², substantially as shown and described.

3. In a motor, the disks A and B, the casing D, having the openings D' and D², and the cross-pieces I and J, in combination with the shaft E, the crank-arm E', the wheel F, having

the slots F' and the rim F², the stud G, having the bearing G', and the arms H, of which the upper part, H', has its bearing in the respective recesses F' of the wheel F, substantially as shown and described.

JOHN BURRY.
